UNITED STATES PATENT OFFICE.

VICTOR NIVOIS, OF NEW YORK, N. Y.

DESIGN FOR THE ORNAMENTATION OF WATCH-CASES.

SPECIFICATION forming part of Design No. 13,984, dated June 19, 1883.

Application filed March 27, 1883. Term of patent 7 years.

To all whom it may concern:

Be it known that I, VICTOR NIVOIS, of the city, county, and State of New York, have invented and produced a new and original Design for Ornament for Watch-Cases, of which the following is a full, clear, and exact description.

The object of my invention is to provide a new design for an ornament for watch-cases.

Reference is to be had to the accompanying drawings, forming part of this specification, in which similar letters of reference indicate corresponding parts in both the figures.

Figure 1 is a plan view of the back of a watch-case provided in part with my newly-designed ornament. Fig. 2 is a sectional perspective view of a watch-case provided with my newly-designed ornament.

My newly-designed ornament consists of a circle formed of a series of pointed arches or bows, A, having their ends united and having three-leaved ornaments B, known as "Shamrock," on the united ends of the bows. The bows or arches A and the shamrock B are produced in relief, the inner boundary thereof showing the main characteristics as stated—namely, a series of pointed or lancet arches

joined at their bases by three curves in the form of a three-leaved clover or shamrock, the outer boundary being a circle, and the triangular depression between the arches bounded on the sides adjacent to the arches by lines nearly parallel thereto, and on the side opposite by an arc parallel to the outer circular boundary, and the background on which they are produced can be left plain or can be stippled.

The above-described ornament can be produced along the edge of the cap C on the bevel D of the same, or on the outer surface of the center E. The bows or arches can be made larger or smaller and be more or less pointed.

I claim—

The herein-described design for ornamenting watch-cases, consisting of a circle of pointed or lancet arches, united at their bases by representations of the shamrock raised in bas-relief, and having triangular depressions between the arches and circle, as shown and described.

VICTOR NIVOIS.
